UNITED STATES PATENT OFFICE

CHARLES J. HEILEMAN, OF PARK HILLS, COVINGTON, KENTUCKY

WRIST-WATCH BAND

Application filed February 21, 1929. Serial No. 341,792.

This invention relates to wrist-watch bands and its prime object is to provide an extensible wrist-band that is well adapted to be easily passed or slipped over the hand to and from using place on the wrist and at the same time remain a continuous band that is free from any undue spring or drawing tension but otherwise avoiding any liability of the band to drop from said using place. Another material object is to provide a band that possesses all the advantages of adjustment of a spring-tension device but eliminating such frailty as may be due to any inherent spring action. Still another object is to provide a practically telescopic arrangement for the extension of the band, which is substantial and readily operative and which, when doubled-up or folded together, will fit snugly in a casing that is adapted to this special purpose, being simple, durable, easily made and maintained and artistic, as well, in appearance.

In the accompanying sheet of drawings— Figure 1 is a plan view showing my improvement, including thereunder, an extensible wrist-band with a watch in normal using place therein; Fig. 2, a longitudinal elevation of the band and watch; Fig. 3, a view similar to Fig. 2, but with the locking-clasp shown thrown open and the band in fully-extended condition for its passing or slipping over the hand of the wearer, to and from using place; Fig. 4, a longitudinal elevation of the band taken by itself, apart from the watch and in fully-extended condition, with a portion in the length of the band broken out near each end thereof, so as to more clearly show the adjustable and detaining features of the band; and Fig. 5, a perspective view showing the extension features but partly folded and prior to encasing in the hinged clasp-member of the device.

In these views, the wrist-band 1 is provided at each end with a hollow or tubular link 2 that is adapted for pivotal-attachment to the opposite forked ends of a watch or timepiece member 3.

The said wrist-band comprises a series of hinged chain links 4, a pair of slideable links 5 and 6, an elongated hinged link 7

and a casing 8, the latter provided with a hinged lid or cover 9 and adapted to contain the said special links 5, 6 and 7 when duly folded or nested together and placed therein, the link 7 being hinged to the casing 8 at 10, while the cover 9 is hinged to the casing at 11. The said links 4 may be of any desirable shape and are so formed that the ends of one link are connected to the body of the next link to make or complete a hinge joint, thus resulting in a flexible or pliable self-adapting and comfortable wrist-watch band.

The first special link 5 of the three specials is preferably and notably of U-shape and a two-pronged link 4 is pivotally secured to the rear transverse portion or bar 12 in the usual manner, thus forming a hinge-joint therewith. The ends 13 of the side-bars 15 of said link 5 are bent or turned inwardly and have openings or eyes 14 that are adapted to slide on the parallel side-bars 16, 16, of the next special link 6 of said three specials, while the ends 17, 17, of the said side-bars 16, 16, are bent or turned outwardly and, also, have openings or eyes 18 therein that are adapted to slide on the said parallel side-bars 15 of said U-shape link 5.

The transverse portion or closed end of the next succeeding special link 7 of said three specials is hinged in the casing 8 at 10, and its outer ends are connected to the cross-bar of the said link 6 to form a hinge-joint therewith.

Within the said casing 8 and, also, on the bottom thereof, I provide a strip 21 of sheet-metal on which the cross-members 19 and 20 of the end of the series of links 4 rest, and, on this strip 21, adapted to form an anchorage for the end of the band 1, I provide a pair of hook-formations or lugs 23^a, 23^b, that are so spaced apart that the chain formed by the series of links 4 can be readily adjusted in length by distances or intervals equivalent to or coincident with half the length of a link of said series 4.

The said specially improvised links 5, 6 and 7 are so made that, when they become telescoped and folded or otherwise laid to-

gether in the casing 8, they practically become but a single thickness of material in the said casing 8, and the cross-member 12 of the said special link 5 is adapted to engage or fit over the hinge 10 at the inner end of the said special link 7 in the casing 8, the outer cross-member 12 contacting with or engaging the lug 22 in the said casing for holding the folded or doubled-up special links in closed place in that casing.

10 The lid or cover-plate 9 of the casing is provided with indentations or upset-notches 23 that are adapted to co-engage the coinciding indentations or upset-notches 24 on said casing for removable snap-connection therewith.

A thumb-piece 25 extends centrally from the outer free end of the said lid 9 for readily opening the clasp when desired.

15 I claim:—

20 In a wrist-watch band, a longitudinally or circumferentially adjustable pair of band-sections each having a series of flexibly-connected link members and with gaps at their opposite ends, one gap being adapted to accommodate the wrist watch for display use and the other gap to contain a connecting clasp casing, a hinged closure lid on the clasp casing, an elongated U-shaped link

25 member in the latter gap connected to one of said band-sections, an elongated link member also of U-shape and slidably connected to the first-named link member, a third U-shaped link member hinged at one end to the

30 second-named link member and at its other end to an eye formation in the clasp casing, said last-mentioned U-shaped link member being adapted to fold upon the first-mentioned link members and be received in

35 said casing, a link contacting lug on said eye formation and a pair of upwardly extending hook formations provided on the inner face of the casing bottom for adjustable engagement with the end links of the other band-section, for adapting the wrist-band to ready slipping or passing over the hand and to accommodate various sizes or girths of hands or wrists, substantially as shown and described.

40 45 50 In testimony whereof I hereunto affix my signature.

CHARLES J. HEILEMAN.
